UNITED STATES PATENT OFFICE

127,809

DESIGN FOR A REMINDER INDICATOR

Gerald M. Meehan, Hart, Mich.

Application March 25, 1940, Serial No. 91,223

Term of patent 7 years

To all whom it may concern:

Be it known that I, Gerald M. Meehan, a citizen of the United States, residing at Hart, in the county of Oceana and the State of Michigan, have invented a new, original, and ornamental Design for Reminder Indicators, of which the following is a specification, reference being had to the accompanying drawing, forming part thereof, in which:

lamp-post and comic character's nose being lined to represent the color red;

I claim:

The ornamental design for a reminder indicator, substantially as shown and described.

GERALD M. MEEHAN.
